(57) **CLAIM**

The ornamental design for a tooth-shaped bottle, as shown and described.

DESCRIPTION

FIG. 1 is a left side top perspective view of the tooth-shaped bottle of the present invention;

FIG. 2 is a right side top perspective view of the tooth-shaped bottle of the present invention;

FIG. 3 is a left side bottom perspective view of the tooth-shaped bottle of the present invention;

FIG. 4 is a right side bottom perspective view of the tooth-shaped bottle of the present invention;

FIG. 5 is a front elevational view of the tooth-shaped bottle of the present invention;

FIG. 6 is a left side elevational view of the tooth-shaped bottle of the present invention;

FIG. 7 is a right side elevational view of the tooth-shaped bottle of the present invention;

FIG. 8 is a top plan view of the tooth-shaped bottle of the present invention; and,

FIG. 9 is a bottom plan view of the tooth-shaped bottle of the present invention.
